UNITED STATES PATENT OFFICE.

LEONARD T. HOOK, OF SEATTLE, WASHINGTON.

MEANS ADAPTING ELECTRIC FLASH LIGHTS FOR TESTING ELECTRIC CIRCUITS.

Application filed January 29, 1927. Serial No. 164,553.

In determining whether or not an electric circuit is intact, a common practice among electricians has been to test the same by a bell and battery, thus necessitating the carrying of instruments which possessed no particular utility in an electrician's work, except for this single purpose. An electric flashlight, however, is a necessary part of the equipment required in such work, and my invention has reference to instrumentalities whereby such a flashlight, in addition to performing its usual functions, may also be utilized in "lamping out" an electric circuit.

The objects of my invention, generally stated, are, to provide, in an electric flashlight of ordinary construction, a slightly modified form of base, and a device adapted to be detachably mounted thereto, having a pair of electrical contact points attachable, for instance, to the respective wires of an electric circuit, and whereby a flash of light will indicate if said circuit is unbroken; and, to afford, such a device which is light in weight, less cumbersome than the other means commonly employed for making such tests, and inexpensive to produce.

In the accompanying drawing—

Figure 1 is a front elevation of the device complete, the connecting wires for a pair of electrical contact clips being shown in broken sections; and,

Fig. 2, a vertical sectional view of the casing of an electric flashlight, broken away, the base thereof, as modified to receive the device, and the other mechanism of the device secured therein, a battery, also broken away, being shown mounted in the casing, and said connecting wires indicated in broken sections.

Referring more particularly to the drawing, 1 denotes the casing of an electric flashlight, 2 a battery disposed therein, and 3 the base of the flashlight adapted to be threadedly engaged with the casing. To this base, which in its general form presents the usual construction, a sleeve 4 is fixedly secured centrally thereof and extends therein, as indicated in Fig. 2, for approximately half the height of the base. A collar 5 is mounted on and slidably engages said sleeve. Said collar is provided in its upper portion with an axially aligned opening reduced in diameter and exteriorly threaded, as at 6, and is put under tension by a strong helical spring 7,

secured to said portion and the lower inner section of the base.

Another member, generally designated as 8, carries an axially aligned upstanding section, the lower portion of which, denoted as 9, is circular in cross section and slidably mounted within the sleeve 4, and its upper portion 10, exteriorly threaded, engages the threaded portion 6 of said collar. A circular outlined and knurled portion 11, having integral therewith an exteriorly threaded section 12 reduced in diameter, provides a base for the member 8, and a cover for a casing 13, which is threadedly engaged with the section 12. Said casing, cylindrical in form, is designed to be made of hard rubber or any other suitable insulating material. A spindle 14, made of material conductive of electricity, having at one end a head 15 and at the other end an exteriorly threaded section 16, is fixedly secured within the member 8, and completely insulated therefrom; the insulation therefor being denoted as 17.

20 designates an electric contact member disposed on but insulated from the spindle, and contacting with the member 8, and 21 an electrical contact member threadedly secured to said spindle, and insulated from the member 8, the said members providing respectively positive and negative pole connections for the device with the flashlight, as will be presently described. An insulated wire, denoted as 22, is secured to each of said contact members by a screw 23, and extends out of the lower end of the casing through a central opening 24 therein, and each is adapted to establish electrical communication from the contact member with which it is thus connected to and through a metallic clip 25, secured to its outer terminal. 26 denotes a rubber protecting tube disposed on each of said wires, and adjacent its clip.

When this modified form of the base is connected with the flashlight, the spring 7 serves to force the collar 5 against the bottom of the battery 2 and thus permit a normal flow of the electric current through the flashlight and thereby let it function as primarily intended, the collar obviously taking the place of the free terminal of a like spring disposed in the base of an ordinary flashlight.

In utilizing the device, the parts connected

with the casing 13 are assembled as heretofore described, the said upstanding section of the member 8 is inserted in the sleeve 4 and the threaded portion 10 of said member 5 is brought into engagement with the threaded opening 6 of the collar. When the device is screwed into place in the flashlight, the upper portion of the collar is withdrawn from its contact with the battery, and the 10 head 15 of the spindle is brought into contact with the bottom of the battery, as indicated in Fig. 2, thus, when the electric current is turned on in the flashlight, diverting it from its normal flow through the flashlight into and through the present device. The electrical contact member 20 derives its 15 electro-motive force through the casing of the flashlight and the elements shown which, as is evident, are adapted to connect it electrically therewith, thereby affording a positive pole connection for the device, and the electrical contact member 21, insulated from said elements and connected with the insulated spindle contacting with the bottom of 20 the battery as described, derives its electro-motive force through the spindle, thereby providing a negative pole connection for the device.

The operating button of the flashlight having been depressed and its usual connecting mechanism slid into a position to keep the light on when the circuit therefor is complete, the device is ready for use in testing an electrical circuit. This is accomplished, 30 as indicated in Fig. 1, by attaching the clips 25 to the wires to be tested, denoted as 27, and if the wires belong to such a circuit and the same is intact, an electrical circuit will be established through said wires, the device 35 and the flashlight, and the flashlight will be illuminated. As said clips are energized electrically, obviously, similar tests may be made by simply touching the clips to opposing points in any other electrical circuit. 40 A linking together of the clips will cause the flashlight to function by the current flowing through it and the device, and when it is equipped with the modified base it is complete as a flashlight. It may be noted, therefore, the device—exclusive of said base—being small, of lightweight construction, and having no parts which are frail or liable to get out of order, may be conveniently carried separately of the base and quickly attached to the flashlight when a test is to be made, or, if desired, it may be carried attached to the flashlight, as shown, without interfering with the uses for which the flashlight was originally designed to be employed. 50 In the present embodiment of the invention, I have shown and described the device as applicable to an electric flashlight having a helical spring disposed in its base, and 55 which serves as a contact with a battery in

the flashlight. As will be obvious to those skilled in the art, the device may also be employed with electric flashlights having such a contact of a different type, and changes in and modifications of the construction described may be made without departing from the spirit of my invention or sacrificing its advantages, hence it is desired that I be not confined to the specific structure set forth. 75

I claim:

1. In combination with an electric flashlight having a detachable base, a sleeve secured to the base, a collar slidably mounted thereover having an interiorly threaded section, a spring adapted to force the collar in contact with the negative pole of a battery in the flashlight, a member having a base portion carrying an upstanding section, a spindle, terminating at one end in a head and at the other end in an exteriorly threaded section, extending through the member and insulated therefrom, said upstanding section slidably engaging the sleeve and threadedly engaging the collar and whereby the collar may be withdrawn from said contact with the battery and replaced by the head, an electric contact member, contacting with the first-named member and insulated from the spindle, adapted to provide a positive pole connection with the flashlight, an insulated casing secured to said base portion, and means secured to said contacts and extending through the casing for establishing an electric circuit through the flashlight and said instrumentalities. 90

2. In combination with an electric flashlight having a detachable base, a sleeve secured to the base, a collar slidably mounted thereover, having an axially aligned opening reduced in diameter and interiorly threaded, a spring disposed in the base and secured to the collar adapted to force the collar in contact with the negative pole of the adjacent battery in the flashlight, a member having a portion circular in cross section surmounted by an exteriorly threaded portion, a spindle extending through the member and insulated therefrom, said member slidably engaging the sleeve and threadedly engaging the collar and whereby the collar may be released from said contact with the battery and displaced by the head, an electric contact member contacting with the first-named member and adapted to afford a positive pole connection with the flashlight, and a second electric contact member secured to the spindle adapted to afford a negative pole connection with the flashlight. 100

3. In combination with an electric flashlight having a detachable base, a sleeve secured to the base, a collar slidably mounted thereover, having in its top portion an interiorly threaded section, spring means dis-

posed in the base and secured to the collar adapted to force the collar in contact with the negative pole of the adjacent battery in the flashlight, a member operable in the sleeve and threadedly engaging the top portion of the collar, and a rod extending through and insulated from the member, said member being adapted to withdraw the collar from said contact and effect a like contact of the rod with the battery, and thereby permit electro-motive force to be diverted from the battery to said rod.

4. In a device of the class described, a base adapted to be attached to an electric flashlight, a sleeve secured centrally of the base, an electrical contact, comprising a collar slidably mounted over the sleeve, said collar having an opening, reduced in diameter, in axial alignment with the sleeve and 15 interiorly threaded, a spring adapted to

force the collar above the base, and a member threadedly engaged with the collar for retracting the same.

5. In a device of the class described having a base adapted to be attached to an electric flashlight, a guide way in said base and a casing interiorly threaded, a connecting member, comprising a circular outlined knurled portion to provide a cover for the casing, an integral exteriorly threaded section, reduced in diameter, at one side of the portion adapted to threadedly engage the casing, an upstanding axially aligned section on the other side of the portion, insertable in the guide way, and an insulated electrical contact member disposed in the connecting member and projecting from the base and the outer terminal of said section.

LEONARD T. HOOK.
